CLAIM

We claim, the ornamental design for a confection, as shown and described.

DESCRIPTION

FIG. 1 is a perspective view of a confection, showing our new design in an exemplary embodiment;
FIG. 2 is a front elevation view of the embodiment shown in FIG. 1;
FIG. 3 is a back elevation view of the embodiment shown in FIG. 1;
FIG. 4 is a side elevation view of the embodiment shown in FIG. 1;
FIG. 5 is a another side elevation view of the embodiment shown in FIG. 1;
FIG. 6 is a top plan view of the embodiment shown in FIG. 1;
FIG. 7 is a bottom plan view of the embodiment shown in FIG. 1;
FIG. 8 is a perspective view of a confection, showing our new design in another exemplary embodiment;

FIG. 9 is a front elevation view of the embodiment shown in FIG. 8;

FIG. 10 is a back elevation view of the embodiment shown in FIG. 8;

FIG. 11 is a side elevation view of the embodiment shown in FIG. 8;

FIG. 12 is a another side elevation view of the embodiment shown in FIG. 8;

FIG. 13 is a top plan view of the embodiment shown in FIG. 8; and,

FIG. 14 is a bottom plan view of the embodiment shown in FIG. 8.

The broken-line disclosure in the views is generally understood to form part of the environment in which the claimed design is embodied.

Also, references to “side,” “bottom,” “front,” and “rear” Figure Description are not necessarily meant to require to the claimed design may be used in any orientation.
